Ira James Ordway

UNITED STATES PATENT OFFICE.

IRA JAMES ORDWAY, OF CHICAGO, ILLINOIS.

APPARATUS FOR HEATING BUILDINGS.

SPECIFICATION forming part of Letters Patent No. 357,332, dated February 8, 1887.

Application filed October 30, 1885. Serial No. 181,367. (No model.)

To all whom it may concern:

Be it known that I, IRA JAMES ORDWAY, of Chicago, in the county of Cook and State of Illinois, have invented a new and useful Improvement in Apparatus for Heating Buildings, of which the following is a full, clear, and exact description, reference being had to the annexed drawings, forming a part of this specification.

10 The object of my invention is to provide an apparatus which will give to each room of a building its own independent supply of hot air; and my invention consists in the construction hereinafter fully described and specifically claimed.

15 In the drawings, Figure 1 is a vertical section of a house, showing my system of heating buildings. Fig. 2 is a vertical section of the furnace.

20 A indicates a house, in the basement of which is located a furnace, B, through which pass the air-flues C, leading to the rooms E, F, and G. The flues C are entirely separate from each other, and are supported in the heads of 25 the furnace, D and H, making a continuous pipe or flue in the furnace, the inner surface of which is used to heat the air.

25 The cold air enters at the bottom of these flues C; and is warmed by the heat in the combustion-chamber, causing the air thus heated to rise to its destination in an unbroken current without being mingled with the air in other flues or chambers leading to other registers.

30 The furnace is provided with two dia- phragms, I and N, which direct the flame and smoke three times across the flues C before entering the smoke-pipe J at its lower outlet. This arrangement utilizes the heat in the com- 35 bustion-chamber by the pressure or "head," as well as by the circulation. The pipes 1, 2, 40 3, and 4 are connected with the flues C, thus

conveying the air heated in the furnace to the rooms in unbroken streams or currents, which greatly facilitates the velocity and increases 45 the quantity of air delivered through the registers, and thereby a large quantity of air is brought in contact with the heating-surface of the heater.

50 The heated air may be delivered through the ceiling or at the farthest and coolest part of the room to be heated, as is represented in the room G, thus producing a thorough circulation of warm air in rooms on the same floor of the furnace, rendering it practicable to heat 55 flats and basement-rooms.

A register in the opening Z enables the use of as much outside air as is desired.

I do not claim herein the construction shown in Patents Nos. 132,554, 306,638, and 326,055. 60 In the first-named patent the hot-air pipes pass longitudinally through the combustion-chamber, which has over it a supplemental hot-air chamber. In the other patents the different pipes shown have independent air-supplies leading either from the rooms to be heated or from the outside of the building, and the combustion-chamber has no deflectors therein, as in the present device.

65 What I do claim is—

70 The combination, with a building having apartments to be heated and pipes leading to said apartments, of a heater for air having a combustion-chamber, vertical air-pipes passing through said chamber and connecting with 75 the pipes leading to the apartments, and horizontal deflectors in the combustion-chamber extending alternately from each side thereof, substantially as described.

IRA JAMES ORDWAY.
